UNITED STATES PATENT OFFICE.

HENRY G. VOIGHT, OF NEW BRITAIN, CONNECTICUT, ASSIGNOR TO THE RUSSELL & ERWIN MANUFACTURING COMPANY, OF NEW BRITAIN, CONNECTICUT.

KNOB-ROSE.

SPECIFICATION forming part of Letters Patent No. 723,951, dated March 31, 1903.

Application filed June 10, 1902. Serial No. 110,958. (No model.)

To all whom it may concern:

Be it known that I, HENRY G. VOIGHT, a citizen of the United States, residing at New Britain, in the county of Hartford and State of Connecticut, have invented certain new and useful Improvements in Knob-Roses, of which the following is a specification.

My invention relates to improvements in knob-roses for door-latches; and the main object of my improvement is to provide a supplemental spring for turning the latch-spindle, which supplemental spring is mounted in the rose, so that it is only necessary to apply the rose to the door in order to provide the knob-spindle with the supplemental spring.

In the accompanying drawings, Figure 1 is a front elevation of my knob-rose. Fig. 2 is a sectional view of the same on the line *xx* of Fig. 1. Fig. 3 is a rear elevation of the same with the cap-plate removed. Fig. 4 is a detached view of the said removed cap-plate, and Fig. 5 is a detached side elevation of the supplemental spring and its hub.

The front side of the rose A is of any ordinary construction. Projecting from the rear side of the rose there is a rim or flange 6, that constitutes the edge of a small case for a hub and spring, the portion of the rose within the circle of the said rim forming the front of the said small case. This rim, as shown, is provided with three lugs 7, that serve as means for attaching the cap-plate 8, that forms the rear side of the said small case. This cap-plate is of a diameter large enough to rest on the rear edge of the rim 6 and is notched or reduced at the edge to form the three recesses 9, that receive the lugs 7, and the bottom of the notches are preferably beveled back on their outer face, as shown in Fig. 4. The cap-plate is secured in place by heading down or riveting the ends of the lugs 7, so that the said cap-plate then becomes, in effect, a permanent part of the rose. I have thus described the cap-plate and its manner of attachment only for the sake of describing a practical form of the device; but the particular detail construction and manner of attaching the cap-plate to the back side of the small case on the rose is not essential to my invention. On the inner side of the rim there

is an inwardly-projecting rib 13, that forms double shoulders. The spring-hub 10 is provided with a square axial hole 11 to fit the ordinary knob-spindle the same as an ordinary latch-hub fits the said spindle. At each end of this hub is a shouldered tenon 12, that is received in the central holes in the front and rear of the small case—that is, in the center of the rose and center of the cap-plate. At one side of the spring-hub there is a hooked arm 14, one member of which stands parallel to the side of the spring-hub at a little distance therefrom, so as to leave a space between. A spring 15 is coiled around this hub under tension, the said spring being provided with hooked ends 16, whereby the ends of the spring after passing through the space between the body of the hooked arm 14 and side of the spring-hub 10 may extend outwardly and bear upon the opposite edges of the body 70 of the said hooked arm and extend radially beyond the said arm, as best shown in Figs. 3 and 5. After the spring is thus assembled on the spring-hub and before the cap-plate is secured to the rose the said spring-hub and 75 spring are inserted within the small case, with the projecting ends of the spring bearing upon the opposite shoulders or side edges of the rib 13, as shown in Fig. 3. The cap-plate may then be secured in place, as before described, 80 and the rose is complete, with the spring-hub and spring properly mounted in suitable journal-bearings, all ready for applying the rose to a door in connection with any ordinary knob-latch having a spring for projecting its 85 latch-bolt. Ordinarily the springs in these latches for projecting the latch-bolt are purposely made very light and easy and will answer all purposes where the knob is symmetrical and round so as to work easily. In some 90 cases, however, an irregular form of knob or a knob-lever is desired, and the ordinary latch-spring may not be sufficient to lift the knob-lever to its proper position and to also throw out the latch-bolt. My rose is especially designed for use in connection with these special knobs or levers, and it is only necessary to furnish the ordinary latch when a special knob is desired with such knob and my rose, so that when the rose is applied the 95 100

knob-spindle may be inserted through the spring-hub in the rose as well as through the latch-hub and the supplemental spring will insure the proper working of the latch-bolt.

- 5 It will be seen that turning the knob-spindle in Fig. 3 so as to carry the hooked arm of the spring-hub toward the right will carry with it that end of the spring which is hooked over the right-hand side of the said arm, while 10 the other end of the spring will be held in its fixed position by its engagement with the left-hand shouldered edge of the rib 13, so that the spring will be wound up under greater tension as the knob-spindle is thus turned. 15 It is also obvious that when the knob is released the tension thus applied will return the knob and spindle to its normal position. Turning the knob-spindle in the opposite direction from its normal position (shown in 20 Fig. 3) will in like manner put the spring under tension the same as before only the opposite ends of the spring are moved by turning the knob in opposite directions.
- I am aware that supplemental springs of a 25 different construction from mine have been applied to a door before the rose is placed in position thereon and for the purpose of assisting the ordinary latch-spring to operate properly in connection with an irregular-shaped 30 knob, and the same is hereby disclaimed. By my improvement the complete rose, with spring and spring-hub, is produced at a small cost, the parts are furnished in their as-

sembled form, and no additional labor is required in putting on the rose other than to 35 merely counterbore the hole for the knob-spindle.

It is apparent that some changes from the specific construction herein disclosed may be made, and therefore I do not wish to be understood as limiting myself to the precise form of construction shown and described, but desire the liberty to make such changes in working my invention as may fairly come within the spirit and scope of the same. 45

I claim as my improvement—

1. The combination of a knob-rose, with the spring-hub and the double-acting spring mounted within and carried by the said rose, substantially as described. 50

2. The combination of a knob-rose, with the spring-hub and the double-acting supplemental spring mounted within the said rose and means for confining the said hub and spring within the said rose, substantially as de- 55 scribed.

3. The combination of a knob-rose, having an axial bearing for a spring-hub with the double-acting spring-hub journaled within the said axial bearing of the said rose, and a 60 double-acting spring between the said spring-hub and rose.

HENRY G. VOIGHT.
